[57] CLAIM

The ornamental design for a dish closure or the like,
substantially as shown.

DESCRIPTION

FIG. 1 is a top perspective view of a dish closure or the
like showing my new design;
FIG. 2 is a side elevational view thereof;
FIG. 3 is a top plan view thereof; and
FIG. 4 is a bottom plan view thereof; and
FIG. 5 is a cross-sectional view thereof on an enlarged
scale taken along line 5—5 of FIG. 2.
